RECOVERY OF PHENOLS FROM MINERAL OILS

Minor C. K. Jones, Elizabeth, and Barney R. Strickland, Roselle, N. J., assignors to Standard Oil Development Company, a corporation of Delaware

Application June 22, 1940, Serial No. 341,818

3 Claims. (Cl. 260—627)

The present invention relates to the refining of mineral oils. The invention is especially concerned with the removal, segregation and recovery of naturally occurring acidic oxygen containing compounds from mineral oils containing the same. The invention is particularly concerned with an improved method for the removal and recovery of petroleum oil phenols and petroleum oil naphthenic acids utilizing a solid reagent selected from the class of alkali metal aluminum silicates of the zeolite type. The present invention not only recovers these valuable materials in an efficient and economical manner, but also produces a high quality treated oil product.

It is known in the art to remove and recover petroleum oil phenols, as well as petroleum oil naphthenic acids by various methods since these materials are relatively valuable and are desirable, for example, as inhibiting agents and as intermediate feed products. One method currently employed is to contact the phenol and naphthenic acid containing petroleum oil with various aqueous solutions of alkali metal hydroxides and the like in order to form the corresponding phenolates and naphthenates. These salts are soluble in and are removed with the spent aqueous alkali metal hydroxide solution. The corresponding phenols are then recovered from the salts by treating the same with dilute acids and the like in order to form the corresponding phenols or naphthenic acids.

We have now discovered an improved method of removing and recovering these valuable constituents from feed oils containing the same in an efficient manner by which a high yield is secured and which also results in the production of a treated oil product of high quality. In accordance with our invention the mineral oil containing the recoverable phenolic type compounds and naphthenic acids is contacted with a solid reagent, selected from the class of alkali metal aluminum silicates of the zeolite type, under conditions to substantially, fully remove these constituents from the feed oil. The spent solid reagent is then handled in a manner to remove, segregate, and recover the phenolic type compounds and naphthenic acids from the reagent and to fully regenerate or revivify the same. The process of our invention may be readily

understood by reference to the attached drawings illustrating modifications of the same.

Figure 1 illustrates a modification of the invention in which the feed oil is passed through a bed of the solid reagent, while Figure 2 illustrates another modification in which a slurry of the solid reagent is utilized. Referring particularly to Figure 1, it is assumed that the phenolic type constituent and naphthenic acid containing feed oil is a petroleum oil boiling in the kerosene oil boiling range. For purposes of illustration it is also assumed that the solid reagent is a naturally occurring hydrated aluminum silicate of the zeolite type and that two zeolite contacting units are employed. It is to be understood that any number of units may be utilized and may be arranged in any desirable manner. The feed oil is introduced into initial contacting unit 1 by means of feed line 3. The feed oil flows upwardly through unit 1 and contacts a bed of zeolite which preferably comprises a small particle size so that a large surface area is secured. Temperature and pressure conditions are adjusted in a manner to substantially completely remove the phenols and naphthenic acids from the feed oil. The feed oil is withdrawn from initial contacting unit 1 by means of line 4, withdrawn from the system and handled in any manner desirable. At the end of a fixed time period in which the effectiveness of the zeolite is decreased to a predetermined efficiency, the feed oil is passed into secondary zeolite contacting unit 2 by means of line 5 and withdrawn by means of line 6. The zeolite in contacting unit 1 containing the adsorbed phenols and naphthenic acids is handled in a manner to remove and segregate these compounds and to regenerate the zeolite. This is preferably accomplished by washing the zeolite with suitable solvents. For the purposes of description it is assumed that the zeolite is initially contacted with a relatively low boiling petroleum oil distillate solvent having a preferential solubility for the petroleum oil remaining in the zeolite bed. This petroleum oil washing solvent may be introduced by means of line 6 and withdrawn by means of line 7. The zeolite bed is then contacted with a solvent having a preferential selectivity for the phenolic type compounds which for the purposes of description are taken to be water. The water is

introduced into initial contacting plant 1 by means of line 9 and withdrawn by means of line 8. Sufficient water is introduced at a temperature and pressure which is adapted to substantially fully remove the phenols from the spent zeolite bed. The zeolite bed, free of petroleum oil and adsorbed petroleum phenols, is contacted with a solvent having a preferential selectivity for the naphthenic acid compounds.

For the purposes of illustration, this solvent is taken to be a 5% sulfuric acid solution which is introduced by means of line 11 and withdrawn by means of line 10. The zeolite bed is treated in a manner to fully regenerate the same. This is preferably accomplished by washing the bed with an additional acid solution which is introduced by means of line 12 and withdrawn by means of line 13, and then contacting the bed with an alkali metal hydroxide solution such as a sodium hydroxide solution, which is introduced by means of line 14 and withdrawn by means of line 15. At the end of the cycle in which the efficiency of the zeolite in contacting unit 2 drops to a certain predetermined point, the feed oil is again passed into the regenerated zeolite in unit 1. The zeolite-contacted oil is withdrawn from contacting unit 2 by means of line 16, withdrawn from the system, and handled as desired. The zeolite in contacting unit 2 containing the adsorbed phenols and naphthenic acids, is handled in a manner similar to that described with respect to unit 1 in a manner to remove and segregate the phenols and naphthenic acids and to regenerate the zeolite. This is accomplished by initially washing the zeolite bed with a relatively low boiling petroleum solvent introduced by means of line 17 and withdrawn by means of line 18, removing the phenolic type constituents by contacting the zeolite with a preferential solvent for the phenolic type compounds which is introduced by means of line 20 and withdrawn by means of line 19. This solvent preferably comprises water. The naphthenic compounds are removed by contacting the zeolite bed with a dilute acid solution which is introduced by means of line 22 and withdrawn by means of line 21. The zeolite bed is regenerated by contacting the same with additional acid which is introduced by means of line 23, withdrawn by means of line 24, and with an alkali metal hydroxide solution which is introduced by means of line 25 and withdrawn by means of line 26. The aqueous solution of phenols which is removed from the respective contacting units by means of line 40 is introduced into phenol recovery unit 27. In this unit, when treating relatively high boiling petroleum oils the relatively high boiling phenols will separate from the aqueous layer. The phenol layer is withdrawn from the phenol recovery unit 27 by means of line 28, while the aqueous layer is withdrawn by means of line 29 and preferably recycled as described as a phenolic solvent to the system. As the petroleum oil contacted is a relatively wide boiling fraction and contains relatively low boiling and relatively high boiling petroleum phenols, it may be desirable to fully recover the relatively low boiling phenols from the aqueous layer by distilling the same prior to returning the aqueous layer as solvent to the zeolite contacting units. This is accomplished by passing the aqueous layer to still 30, distilling the same under operating conditions adapted to remove overhead the aqueous layer by means of line 31, and to remove as the bottoms the rela-

tively low boiling phenolic constituents by means of line 32.

The acid solvent containing the naphthenic constituents, removed from the respective contacting plants by means of lines 10 and 21, respectively, is similarly handled in a manner to segregate the naphthenic acids. The acid solvent is introduced into naphthenic acid recovery plant 33 in which a layer separation will occur between the acid solution and the naphthenic acids. The naphthenic acids are removed by means of line 34 and further refined as desired, while the acid layer is withdrawn by means of line 35 and preferably recycled as acid solvent to the contacting plants as described.

Referring specifically to Figure 2, feed oil is introduced into the system by means of line 50. The feed oil is mixed with a quantity of zeolite which for purposes of illustration is taken to be powdered zeolite and which is introduced from zeolite bin 51 by means of screw conveyor 52. The oil and the zeolite are passed through mixer 53 and passed as a slurry by means of line 54 into agitating plant 55 which may comprise any suitable number of agitating units arranged in any desirable manner. Complete mixing is secured by means of agitator 56. The mixture is withdrawn from plant 55 by means of line 57 and introduced into settling unit 58. The separation of the solid phase from the liquid phase may be facilitated by any desirable means such as baffles, settling means, and the like. The treated oil is withdrawn from unit 58 by means of line 59 and handled in any desirable manner. The zeolite containing adsorbed thereon the phenolic type compounds and naphthenic acids is withdrawn from unit 58 by means of line 60 and handled in a manner to remove and recover the phenols and naphthenic acids and to substantially fully regenerate the zeolite. This is preferably accomplished by passing the zeolite to washing unit 61 in which the occluded relatively high boiling petroleum oil constituents are removed by washing with a relatively low boiling petroleum oil solvent which is introduced by means of line 62 and withdrawn by means of line 63. The washed zeolite is introduced into phenol recovery unit 64 by means of line 65, in which the phenols are removed by contacting the zeolite with a solvent having a preferential solubility for phenolic type compounds. For the purposes of illustration it is assumed that the solvent comprises water, which is introduced by means of line 66 and withdrawn by means of line 67. The zeolite is passed to naphthenic acid recovery unit 68 by means of line 69 in which the naphthenic acids are removed from the zeolite by contacting with a suitable solvent which for the purposes of description is assumed to be a dilute acid solution which is introduced by means of line 70 and withdrawn by means of line 71. The zeolite, free of adsorbed phenolic type compounds and naphthenic acid type constituents, is handled in a manner to substantially fully regenerate the same. This is preferably secured by passing the zeolite to acid contacting stage 72 by means of line 73 and treating the same with an additional quantity of dilute acid which is introduced by means of line 74 and withdrawn by means of line 75. The acid treated zeolite is passed to contacting unit 76 by means of line 77 and contacted preferably with an alkali metal hydroxide solution which is introduced by means of line 78 and withdrawn by means of line 79. The zeolite is

withdrawn from the latter stage by means of line 80 and recycled to the system as described. The aqueous solution of phenol, withdrawn from unit 64 by means of line 61, is passed to phenol recovery unit 81 in which a layer separation occurs between the relatively high boiling phenols and the aqueous solution. The relatively high boiling phenols are withdrawn by means of line 82, while the aqueous solution is withdrawn by means of line 83 and recycled to unit 64. The phenolic layer is withdrawn by means of line 82, distilled or further refined in any manner desirable. Under certain conditions when the petroleum oil treated is of a relatively wide boiling range and the aqueous solution contains relatively low boiling soluble phenols, it may be desirable to distill the aqueous solution withdrawn from recovery unit 81 in order to remove the relatively low boiling phenols prior to recycling the aqueous solution to unit 64. The acid solution containing the naphthenic acids withdrawn from unit 68 by means of line 71 is passed to naphthenic acid recovery unit 84 in which a layer separation occurs between the naphthenic acids and the dilute acid solution. The naphthenic acids are withdrawn from the system by means of line 85, distilled or further refined in any manner desirable. The dilute acid solution is withdrawn from unit 84 by means of line 86 and recycled to unit 68.

The processes of the present invention may be widely varied. Although the method may be employed for the recovery and segregation of phenolic type constituents and naphthenic acids from any feed oil, it is particularly applicable in the recovery of relatively high boiling petroleum phenols and petroleum naphthenic acids from petroleum oils boiling in the gas oil and lubricating oil boiling range. These substances, due to their characteristics, have heretofore been relatively difficult to segregate.

The adsorbent employed is selected from the class of alkali metal aluminum silicates of the zeolite type, but preferred materials are naturally occurring hydrated alkali metal aluminum silicates, particularly a naturally occurring hydrated sodium aluminum silicate. Although a relatively large particle size may be employed, in general it is preferred to employ zeolite of relatively small particle size, particularly powdered zeolite.

The operating conditions likewise may be widely modified. The flow of the respective treating agents may be either upflow or downflow. Temperatures and pressures may vary and will depend upon the particular feed oil being treated, the quantity and character of the phenols and naphthenic acids present, as well as upon the particular zeolite being used and upon the feed rates and particle size. In general it is preferred to employ atmospheric temperatures and pressures, although temperatures in the range from about 30° F. to 250° F. may be employed in particular instances. If the petroleum oil be of a relatively high viscosity, it may be desirable to employ heating means or to dilute the oil with an inert dilution solvent, as for example a relatively low boiling petroleum oil or with a relatively low boiling hydrocarbon constituent. The feed rates may vary considerably depending upon the general operating conditions, the character of the feed oil being treated, as well as upon the type of zeolite being employed. When the process comprises the utilization of stages, feed rates are in the general range from one to seven volumes of oil per volume of zeolite

per hour. The preferred rates are from two to four volumes of oil per volume of zeolite per hour. When employing a slurry, the amount of slurry is preferably in the range from one volume of zeolite per fifteen to twenty-five volumes of oil.

Although it is not essential, it is preferred that the zeolite after contact with the oil be washed with a solvent which will remove occluded oil portions from the zeolite prior to treating the zeolite to remove the adsorbed phenols and naphthenic acids. This solvent may be any relatively low boiling hydrocarbon. A desirable material comprises naphtha boiling in the range from about 300° F. to 420° F.

The phenols are preferably removed from the zeolite by treating with water at normal temperatures and pressures. The amount of water employed may vary widely depending upon the quantity of phenols present and the particular zeolite employed. In general it is preferred to employ from about one to four volumes of water per volume of zeolite in order to displace the phenolic type constituents. A preferred modification of utilizing water at normal temperatures and pressures for the displacement of the phenolic type constituents is to agitate the mass with air or a similar agitating means. Under certain conditions it may be desirable to employ heated water or steam in order to remove the phenols, although in general this method is not preferred. The aqueous solution, after removal from the zeolite bed, will form two phases comprising a phenol phase and an aqueous water phase. The phenol phase is separated and may be further refined in any manner desirable. Although the aqueous phase may be distilled in order to remove any relatively low boiling soluble phenolic type compounds present, it is preferred to recirculate the same as a phenol solvent directly to the zeolite contacting units.

The acid solution employed for the removal of the naphthenic type constituents from the zeolite likewise may vary considerably. Any mineral acid may be employed, although in general it is preferred to utilize a dilute sulfuric acid having an acid concentration in the range from about 2% to 10%. A particularly desirable solvent for removing naphthenic type constituents from the zeolite comprises a 5% sulfuric acid solution. This solution, after the removal of the naphthenic acid constituents, is likewise preferably recycled to the system as described.

The spent zeolite, free of naphthenic acid and phenolic type constituents, may be handled in any suitable manner in order to regenerate the same. Although the spent zeolite, free of the phenols and naphthenic acid constituents, may be satisfactorily regenerated by washing with additional water, or by washing with a 95% ethyl alcohol solution or equivalent, it is preferred that the spent zeolite be regenerated by treating with an additional quantity of acid, followed by contacting the same with an alkali metal hydroxide solution. The acid preferably is a dilute sulfuric acid solution having an acid concentration in the range from about 2% to 10%. Usually before again contacting the zeolite with additional feed oil, it is preferred to dry the zeolite by any suitable means.

In order to further illustrate the present invention, the following examples are given which should not be construed as limited the same in any manner whatsoever.

Example 1

A petroleum distillate boiling in the kerosene boiling range, having a phenol number¹ of 200, was contacted with a zeolite of the following composition at atmospheric temperatures and pressures:

	Weight, per cent
Na ₂ O	1.51
Al ₂ O ₃	5.69
SiO ₂	45.67
Fe ₂ O ₃	27.11
CaO	2.00
MgO	4.74
Carbon as carbonate	1.18
Per cent ignition loss	8.50

¹ A 200 phenol number is equivalent to 0.2% of phenols, expressed as equivalent milligrams of tertiary amyl phenol per 100 millilitres of oil.

The results of the operations were as follows:

	Phenol number
Feed stock	200
Zeolite contacted stock (fresh zeolite)	0
Zeolite contacted stock (partially spent zeolite)	20

By contacting the zeolite initially with about two volumes of water per volume of zeolite at atmospheric temperatures and pressures and simultaneously blowing with air, substantially the entire quantity of phenols were displaced and separated as an oily layer with the water. The naphthenic acids were displaced and separated by contacting the zeolite with a 5% sulfuric acid solution.

The spent zeolite was regenerated in a number of operations as follows:

Operation	Treated with—	Per cent regeneration
1	Additional acid and sodium hydroxide	100
2	95% ethyl alcohol	75
3	Wet steam	50
4	Benzene	0
5	Burned at 800° F. to 900° F.	25

Example 2

A Talang Akar kerosene was treated in a manner to remove the naturally occurring acidic oxygen containing compounds by contacting the same with zeolite. The result of this operation with respect to the character of the treated oil was as follows:

10	Color	Direct oxidation color
Original Talang Akar kerosene	+13 Saybolt	34 Robinson
(1) After passage through zeolite	+20 Saybolt	+17 Saybolt

Apparently the solid reagent of the present invention reacts with the naturally occurring acidic oxygen containing compounds to form reaction products which may be readily regenerated from the reagent. The regeneration operation may be controlled in a manner to preferentially first, regenerate the phenolic type constituents which may be separated. After separation of the phenolic type constituents the naphthenic acid constituents may be readily regenerated and separated.

What we claim as new and wish to protect by Letters Patent is as follows:

1. Process for the recovery of naturally occurring phenols from mineral oils which comprises contacting feed oils containing these compounds with a solid zeolite under conditions to remove these compounds from the oil, separating the oil and the solid reagent and recovering the naturally occurring phenol compounds from the solid reagent.

2. A process in accordance with claim 1 in which said oil is a petroleum oil boiling in the kerosene boiling range and in which said solid reagent is a naturally occurring hydrated sodium aluminum silicate.

3. Process as defined by claim 1 in which the naturally occurring phenols are recovered from the solid reagent by initially treating the reagent with water and then treating the reagent with a dilute acid solution.

MINOR C. K. JONES,
BARNEY R. STRICKLAND.
